COMBINATION BATHROOM UNIT

Rudolph L. Stephany, 705 E. Ludington Ave.,
Ludington, Mich. 49431

Filed Apr. 19, 1965, Ser. No. 84,867

Term of patent 14 years

(Cl. D4—4)

FIGURE 2 is a section on the plane 2—2 of FIGURE 1, with the drawers under the bathtub unit being in an alternative position from FIGURE 1, and extended to form steps.

The faucet fixtures and water closet, shown in broken lines, are included for illustrative purposes only.

I claim:

The ornamental design for a combination bathroom unit, as shown and described.
